(57) **CLAIM**

The ornamental design for a pet water dispenser as shown and described.

DESCRIPTION

FIG. 1 is a perspective view of a pet water dispenser showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and

FIG. 9 is an enlarged detail view as designated in FIG. 1; and,

FIG. 10 is an enlarged detail view as designated in FIG. 1. The broken lines depict portions of the pet water dispenser and form no part of the claimed design.

The dot dash line is included for the purpose of illustrating the bounds of the enlarged view and forms no part of the claimed design.
